FEED CRUSHER

David D. Fehr, Haskett, Manitoba, Canada

Application March 1, 1940, Serial No. 321,781

2 Claims. (Cl. 83—8)

My invention relates to improvements in feed crushers and the principal object of my invention is to provide a device of the character herewithin described in which means are provided for automatically regulating the volume of feed delivered to the crusher discs according to the rate of speed at which the same are rotating.

A further object of my invention is to provide a device of the character herewithin described wherein the feed conveyor becomes automatically disconnected from the driving shaft when an obstruction comes in contact therewith.

A further object of my invention is to provide a device of the character herewithin described in which a novel mechanism is incorporated for bringing the crusher discs into action.

A further object of my invention is to provide a device of the character herewithin described whereby a more positive delivery of the feed to the crusher discs is facilitated by an improved positioning of the conveyor screw.

A further object of my invention is to provide a device of the character herewithin described wherein the mounting of the driving pulley does not in any way interfere with the placing of the driving belt thereon.

A further object of my invention is to provide a device of the character herewithin described which is of a simple and economical construction and may readily be dismantled for the purposes of inspection and repair.

With the above more important objects in view and such other minor objects as may appear as the specification proceeds, my invention consists essentially in the arrangement and construction of parts all as hereinafter more particularly described, reference being had to the accompanying drawing, in which:

Figure 1 is a longitudinal cross-sectional elevation of my invention.

Figure 2 is a plan view thereof, showing the same as being partially broken away to reveal the hinged connections of my feed regulating means therein incorporated.

Figure 3 is an end view of my feed regulating means.

Figure 4 is a perspective illustration of my hopper conduit retaining means and the control lever associated therewith.

In the drawing like characters of reference indicate corresponding parts in the different figures.

Referring now to the accompanying drawing, my invention will be seen to comprise a feed crusher 1 consisting of a cylindrical housing 2 open at one end 3 thereof and suitably attached

to a mounting base 4. The closed end 5 of the housing is provided on its inner side with an annular bearing retaining ring 6 and a bearing supporting sleeve 7 having a concentric aperture 8 formed centrally therethrough, projects outwardly from the outer surface 9 thereof.

Positioned within the ring 7 I provide an anti-friction bearing 10 concentrically aligned with a similar bearing 11 mounted on the free extremity of the sleeve 7, in which bearings a floating drive shaft 12 is journalled, the tapered end 13 thereof projecting somewhat beyond the extremity of the sleeve, and its opposite end 14 extending partially into a delivery conduit 15 hereinafter to be described.

An open-ended drive pulley 16 is provided with an annular groove 17 on the inner surface thereof to receive the outer ball race of the bearing 11 and a retaining insert 18 equipped with a tapered bore 19 and a circumferential flange 20 is secured upon the shaft end 13 to engage the interior of the pulley 16 and bear against the bearing 11.

A suitable axle nut 21 may of course be provided to retain the insert 18 in position and it will be clearly apparent that by the aforesaid means sufficient rigidity between the pulley 16 and the shaft 12 will be obtained.

Within the interior of the housing 2 and secured to the shaft 12 by means of a key 22 I provide a face plate 23 attached to which in turn by means of the screws 24 is a rotating crusher disc 25 of a conventional design, the plate 23 also being provided on the perimeter 26 thereof with a plurality of radially extending fins 27.

The aforesaid end 14 of the shaft 12 carries a worm conveyor 28 freely mounted thereon, a compression spring 29 and a loose bushing 30 being interposed on this shaft between the plate 23 and the conveyor 28 to urge the latter against a suitable locked nut 31 secured to the end 14 of the shaft 12.

My feed hopper 32 is removably attached to the vertical arm 33 of the aforesaid L-shaped delivery conduit 15, the opposite or horizontal arm 34 of which in turn, is slidably insertable into the open end 3 of the housing 2.

A stationary crusher disc 35 is secured by means of the bolts 36 to the end wall 37 of the conduit arm 34, and it will be noted in this connection that this wall and also both of the plates 25 and 35 are provided with central apertures 38, 39 and 40 respectively, to accommodate the shaft 12 and the associated spring 29, and

that a suitable discharge conduit 41 communicates with the housing 2 at essentially the location of the crusher plates therein.

The means for sliding the conduit 15 within the housing end 3 comprises a pair of guide rods 42 and 43 attached to the latter and extending on either side of the conduit through a pair of eye brackets 44 attached to the latter, and a pair of compression springs 45 are interposed between these brackets and the housing 2 for a purpose to be hereinafter described.

The free extremities 46 of the rods 42 and 43 are threaded to accommodate a pair of knurled adjusting nuts 47 and a removable cross-bar 48 pressed by means of the springs 49 is slidably mounted upon the rods clear of the location of the conduit 15.

One end of this bar is provided with a suitable handle 50 and a vertical recess 51 to engage the rod 42 while the remaining rod 43 engages a horizontal recess 52 formed in the opposite end 53 thereof.

A control rod 54 equipped with a pair of cams 55 on the boss 56 thereof, is rotatably mounted on the rod 43 adjacent the end 53 of the bar 48, the cams thereof being designed normally to engage the recess 52 but to bear against the end 53 of the bar 48 when the lever 54 is rotated. Finally, it will be noted in this connection that the center portion of the bar 48 is outwardly concaved as at 57, this concavity being provided with a suitable threaded bore to accommodate a hand adjustable contacting screw 58, the free end 59 of which in turn frictionally engages the side wall 60 of the vertical conduit portion 33. A threaded boss 61 of a locking lever 62 is provided to bear against the cross-bar 48 and prevent undesired rotation of the screw 58.

Describing now the construction of my feed regulating means 63, the same will be seen to consist of an open-ended sleeve 64 secured within the conduit portion 34 concentrically with the shaft 12 and having an oblique inwardly extending flange 65 formed at one end thereof. Adjacent the interior side of this flange I provide a pair of semicircular trap doors 66 pivotally connected by means of the pin hinges 67 to the diametrically opposite sides of the sleeve 64, and it will also be noted that a circular aperture 68 is formed at the center of the doors 66 to accommodate the aforesaid conveyor 28 therein. A pair of extension brackets 69 are also secured to these doors, the free extremities of such brackets pivotally engaging a pair of control rods 70, which in turn protrude on the exterior of the conveyor portion 34 and each carry a coil spring 71 and a wing-nut 72, whereby the doors 66 are normally maintained in a closed position.

Having thus described my invention, I shall now present its method of operation.

When my feed crusher 1 is in operation, the feed will gravitate from the hopper 32 into the delivery conduit 15, where it will contact the conveyor screw 28 and be urged by the rotation thereof past the doors 66 and through the apertures 38 and 40, between the crusher discs 25 and 35. When these discs and the associated conveyor are rotated at a given rate of speed, the latter will impart a certain pressure to the feed, which in turn will result in the opening of the doors 66 to a definite extent. When, however, this rate of speed is increased or decreased, the conveyor pressure will vary accordingly and the doors will in turn open to a greater or lesser extent, whereby the volume of feed admitted to the discs by the

conveyor will be in an essentially direct proportion to the speed at which such discs may be rotating.

The movement of the doors 66 is of course controlled by the resiliency of the springs 71 and by manipulating the nuts 72 a tensioning adjustment of this movement under various operating conditions will be facilitated.

I also wish to point out that since the conveyor is driven only frictionally from the shaft, that is by its frictional contact with the nut 31 and the disc 25 as effected by the spring 29, the rotation of such conveyor will automatically be discontinued when an obstruction is encountered, such obstruction merely fouling the conveyor and causing the same to slip on the shaft 12.

When setting my crusher in operation, the control lever 54 should first be rotated and the cams 55 thereof disengaged from the recess 52 to contact the bar 48. Thereupon the end 53 of the latter will be forced in the direction of the arrow 73 accompanied by a corresponding movement of the screw 58, which in turn will slide the conduit 15 further into the housing end 3 and result in shifting of the disc 35 towards the disc 25. Thereupon the drive shaft 12 may be rotated and the crushed feed of course will be expelled from the housing 2 through the conduit 41 by the centrifugal action of the fins 21. An additional and 30 a finer adjustment for spacing the discs 25 and 35 to compensate for various conditions of operation and wear is provided by the nuts 47, which may be turned to govern the compression force exerted by the spring 49 against the bar 48, and 35 also by rotation of the contacting screw 58 to alter the spacing of the conduit 15 with respect to this bar.

When the crusher has been stopped, the plates 25 and 35 will of course be drawn apart by the springs 45 acting against the brackets 44 to slide the conduit 45 outwardly from the housing end 3.

Finally in connection with my floating drive shaft arrangement wherein both the drive pulley 16 and the bearings 10 and 11 are positioned on 45 one end of the shaft 12 with respect to its midpoint. I wish to point out that by this means a simple installation of the driving belt on the pulley is facilitated since no obstruction such as a bearing bracket or the like at the pulley end of the shaft renders the same inaccessible.

Since various modifications can be made in my invention as hereinabove described and as illustrated in the accompanying drawing, and many apparently widely different embodiments of same 55 made within the scope of the claims without departing from such spirit and scope, it is intended that all matter contained in the accompanying specification and drawing shall be interpreted as illustrative only and not in a limiting sense and 60 I desire only such limitations placed thereon as are specifically expressed in the accompanying claims.

What I claim as my invention is:

1. In a feed crusher utilizing a screw conveyor 65 to feed material from a hopper to a pair of grinding discs at the end of said conveyor, a pair of hingedly mounted, spring closed trap doors between said hopper and said discs, said trap doors being positioned vertically upon either side of said conveyor, the free edges of said trap doors being semicircular to embrace said conveyor but being slightly spaced from the flight of said conveyor, said doors being yieldable during the feeding of material by said conveyor from said hopper to said discs.

2. A feed crusher comprising in combination, a housing enclosing a crushing chamber, a vertical L-shaped duct extending freely and horizontally into said chamber, a vertically positioned, stationary, crushing plate, secured to the end of said duct and within said chamber, a horizontally positioned screw conveyor mounted upon a drive shaft, extending into said duct, a rotatable crushing disc keyed to said shaft and within said chamber, means for permitting limited horizontal linear movement of said duct during the

10

operation of said crusher and a pair of spring closed trap doors hingedly secured to said duct, said trap doors being positioned vertically upon either side of said conveyor, the free edges thereof being semicircular to embrace said conveyor but being slightly spaced from the flight of said conveyor, said doors being yieldable during the feeding of material by said conveyor through said duct to said crushing chamber.

DAVID D. FEHR.
